COIN INSERTION SLOT

Walter L. Koch, Caldwell, and Kerry A. Day, Parsippany, N.J., assignors to Rowe International, Inc., Whippany, N.J., a corporation of Delaware

Filed Sept. 27, 1968, Ser. No. 13,745

Term of patent 14 years

Int. Cl. D20—01

U.S. Cl. D52—3

Fig. 3

Fig 7

Fig 5

Fig 6

FIGURE 1 is a front elevation of a coin insertion slot showing our new design.

FIGURE 2 is a sectional view thereof taken along the line 2—2 of FIGURE 1.

FIGURE 3 is a rear elevation thereof taken along the line 3—3 of FIGURE 2.

FIGURE 4 is a top plan view thereof taken along the line 4—4 of FIGURE 1.

FIGURE 5 is a side elevation thereof taken along the line 5—5 of FIGURE 1, the other side being a mirror image.

FIGURE 6 is a bottom plan view thereof taken along the line 6—6 of FIGURE 1.

FIGURE 7 is a perspective view thereof viewed from the top left.

The dominant features of our design reside in the portions shown in full lines, the portions shown in broken lines being normally concealed from view.

We claim:

The ornamental design for a coin insertion slot, substantially as shown and described.
